UNITED STATES PATENT OFFICE.

WILBERT A. BURKET, OF SIDNEY, OHIO, ASSIGNOR TO THE SIDNEY MANUFACTURING COMPANY, OF SIDNEY, OHIO, A CORPORATION OF OHIO.

RUNABOUT-SEAT.

1,135,761.

Specification of Letters Patent. Patented Apr. 13, 1915.

Application filed November 25, 1913. Serial No. 803,021.

To all whom it may concern:

Be it known that I, WILBERT A. BURKET, a citizen of the United States, residing at Sidney, in the county of Shelby and State 5 of Ohio, have invented certain new and useful Improvements in Runabout-Seats; and I do hereby declare the following to be a full, clear, and exact description of the invention, such as will enable others skilled 10 in the art to which it appertains to make and use the same.

This invention relates to improvements in seat construction for carriages, etc., and an object of the invention is to provide a rigid 15 seat construction made durable by having two metal connections between the body of the seat and the devices for supporting the back.

Another object of the invention is to provide a convenient seat construction wherein the braces for the back do not interfere in any way with the body of the seat.

With these and other objects in view, the invention consists in certain constructions, 25 combinations and arrangements of the parts which will be hereinafter fully described and claimed.

In the accompanying drawings wherein similar reference characters designate corresponding parts: Figure 1 is a perspective view of the complete seat; Fig. 2 is a section taken on line 2—2 of Fig. 1; Fig. 3 is a section taken on line 3—3 of Fig. 1, the sectional view being taken in the direction of 35 the arrows.

The general aim of the invention is to provide along the top of the seat body a metal rod over which sheet metal is rolled, and to which are secured braces to support 40 the rail and the back of the seat. The braces are so arranged as not to interfere with the convenience of those using the seat and are so placed as not to extend inside the seat body.

Referring to the drawings, the seat will 45 be seen to comprise the ordinary bottom board 1 to which is secured in any suitable manner, the flaring body composed of a sheet 2 bent substantially as shown in the drawing, said sheet having around its lower edge an inturned flange 3 for attachment to the bottom 1 and around its upper edge an outturned flange 4. Overlying the latter 50 is a metal bead or rod 5 held by means of bolts or rivets or other securing means 6 which

pass through the flange and the rod 5. A number of these bolts or rivets 6 are employed, their heads countersunk into the upper side of the rod 5 as seen in Fig. 3.

Referring to Fig. 2, it will be seen that 60 the rail brace 7 is enlarged as at 8, and is provided with a reduced shoulder 9 from which extends a depending shank 10 passing through the bead 5, and having the head 11 thereof countersunk in the bottom 65 of the bead or rod 5. In order to give a pleasing appearance to the bead 5, and to secure the brace 7 in place, there is provided a sheet metal shell or covering 12 which is made in the form of a strip laid 70 over the rod or bead 5, and then bent closely around said rod and with its edges 14 passed between the rod and the horizontal flange 4, as shown in Figs. 2 and 3. The metallic shell rests on the flange 4 and is held firmly 75 against the shoulder 9. The shell 12 may be provided with a number of openings 13 through which extend the shanks 10 depending from the braces 7, or any other method may be used for inclosing the bead 80 or rod 5 with a metallic shell 12.

By referring to Fig. 2, it will be seen that the shanks 10 do not extend through the lower side of the shell, whereas by referring to Fig. 3, it will be seen that the bolts 6 85 extend through the flange 4 and between the lower edges 14 of the shell 12, but not through the upper wall of the shell 12, so that no screws, rivets, bolts or other means appear upon the surface of the shell 12 to 90 mutilate the same, and the only opening through the shell is that directly beneath the shoulder 9, and enlarged portion 8 of the brace. These elements protect the openings from the entrance of water which 95 would rust the rod and the shell, and the clamping of the rod and shell tightly down onto the flange 4 prevents the entrance of water between the lower edges 14. Therefore the parts are thoroughly protected 100 against rust and injury.

The back braces 15 are identical in their construction and connection with the bead 5 and shell 12, with the rail braces 7, with the exception that there are not provided on the braces 15 enlarged portions 8, although 105 of course if desired, this can be done.

What I claim is:

A seat whose body has an outwardly projecting flange around its upper edge, a rod 110

overlying said flange, and a sheet metal covering inclosing said rod; combined with rivets passing through the flange, the lower side of the cover, and the rod and having 5 their heads countersunk in the upper side of the latter, and rail braces whereof each is enlarged near its lower end, has a shoulder beneath the enlargement, and has a reduced shank extending from the shoulder down- 10 ward through the upper side of the cover-

ing and completely through the rod, with a head at its lower extremity countersunk in the lower side of the rod.

In testimony whereof I affix my signature in presence of two witnesses.

WILBERT A. BURKET.
